UNITED STATES PATENT OFFICE.

FRANCIS EDWIN EDWARDS, OF CRYSTAL LAKE, ILLINOIS, ASSIGNOR TO STROMBERG
MOTOR DEVICES COMPANY, OF CHICAGO, ILLINOIS, A CORPORATION OF ILLINOIS.

FUEL-FEED SYSTEM.

1,306,999.

Specification of Letters Patent. Patented June 17, 1919.

Application filed February 16, 1918. Serial No. 217,701.

To all whom it may concern:

Be it known that I, FRANCIS EDWIN EDWARDS, a citizen of the United States, residing at Crystal Lake, in the county of McHenry and State of Illinois, have invented a certain new and useful Improvement in Fuel-Feed Systems, of which the following is a full, clear, concise, and exact description, reference being had to the accompanying drawings forming a part of this specification.

My invention relates to fuel feed systems for automobiles and the like.

The present invention is in general an improvement upon my prior invention of the same general nature set out in my application, Serial No. 204,484, filed November 30th 1917.

In that application I have set out the general advantages of my invention over prior fuel feed systems, particularly of the gravity feed and vacuum fuel feed systems of the prior art.

The essential improvement forming the basis of the present invention lies in the employment of means for controlling the application of the pumping impulses of the column of air in the pumping chamber by means of a float controlled vent of the pumping chamber.

In the accompanying drawings in which I have illustrated one embodiment of my invention—

Figure 1 is an elevational view, partly sectional and partly diagrammatic of an embodiment of my invention;

Fig. 2 is a vertical cross section of the pumping chamber;

Fig. 3 is a plan view of the same;

Fig. 4 is a fragmentary view of a modification showing the float controlling the air vent only and

Fig. 5 is a vertical cross section similar to Fig. 2 of a modification.

In Fig. 1 I have illustrated my invention as adapted to a system for supplying liquid fuel from the main tank 1 to the float chamber 3 of the carburetor 2 of an internal combustion engine. It is to be understood that the invention may be employed for feeding lubricating oil to a bearing or for other purposes, as will be apparent from the following specification.

I provide a pumping chamber 4, the in-

terior of which communicates by way of a tube 5 of relatively small diameter with a cylinder 6. The cylinder 6 with the connecting tube 5 comprise in effect an air containing chamber which, by means of the piston 7 fitting in the cylinder 6, is adapted to receive pumping impulses of alternate compression and rarefaction due to the reciprocation of the piston 7. The piston 7 is connected by means of a pitman 8 to an eccentric 9 driven by a shaft 10. This shaft 10 is preferably connected to the cam shaft of the engine or such other moving part as will insure operation of the piston when the engine is running.

The pump cylinder 6 is connected by a suitable bracket 11 to a frame member 12 of the automobile. It will be noted that the cylinder 6 is provided with a cylinder head 13 and that no valves are employed in this cylinder or head.

The pumping chamber 4 is provided with an integral boss 14 adapted to house the outlet check valve 15, this valve discharging through a pipe or tube 16 to the float chamber of the carburetor.

The pumping chamber 4 is provided with an inlet valve 17 which is adapted to seat on a plug member 18 threaded axially into the bottom of the float chamber. The threaded plug 18 is adapted to support a suitable screen 19 and a cage or housing 20, the inlet of which is connected by way of a pipe or tube 21 with the main fuel supply tank or reservoir 1.

The top of the pumping chamber 4 is closed off by a tight cover 22 which, in this case, is provided with an extending bracket 23 for connecting the same to the bottom of the float chamber 3 of the carburetor.

The cover member 22 has an axial opening in which is threaded a valve seat member 25 forming a suitable vent for the interior of the pumping chamber 4. The vent or plug member 25 is covered by a suitable cage or housing 26 perforated with a number of small openings 27, permitting access to the atmosphere.

A vertical valve stem 28, having a needle valve 29 at its upper end, co-operates with the seat in the plug member 25 to close off the vent when the needle valve is raised. A level controlled member, in this case a float 30, is connected by suitable operating

levers 31 to the valve stem 28 in such manner that when the level of liquid fuel within the chamber 4 rises above a given point the float 30 will rise, lowering the needle valve 29 and opening the vent.

The lower end of the valve stem 28 is guided in a cage 31 and is of such length that when the vent is open the lower end of the stem will engage the inlet check valve 17 and hold the same upon its seat.

The operation of the system thus far described is as follows: Assuming that the main supply tank 1 is filled with gasoline and that the engine is turned over the piston 7 will be reciprocated in the cylinder 6, causing pumping impulses in the column of air in the tube 5 and the inside of the pumping chamber 4. The suction impulses quickly raise liquid fuel through the pipe 21 and the check valve 17 to the pumping chamber 4. The check valve 17 is free to operate as the float 30 is in the lower position and the needle valve 29 is raised to close the vent. As soon as liquid fuel is contained within the pumping chamber 4 it will be discharged through the outlet check valve 15 into the bottom of the carburetor float chamber 3 until said float chamber is filled to the required level, whereupon the float control valve 30 in the float chamber 3 shuts off the admission of further liquid fuel by way of the tube 16. Further operation of the pumping impulses continues to draw fuel from the main tank 1, raising the level in the pumping chamber 4 until the float rises to its upper position, opening the vent 25 and holding the check valve 17 upon its seat.

It is not essential that the valve 17 be held upon its seat as I have found by experiment and I may employ the structure shown in Fig. 4 in which the valve stem 28' does not operate upon the check valve 17. However, the check valve 17, as shown in Fig. 2, positively cuts off the admission of further fuel to the pumping chamber until the level of fuel within this chamber has dropped to the point of releasing the check valve 17.

In case the pumping chamber 4 is placed below the level of the float chamber 3 of the carburetor, there would be no tendency for the fuel in the pumping chamber to discharge by gravity to the float chamber and if the pumping impulses were entirely cut off from the pumping chamber the apparatus would become inoperative after the vents were open. To guard against this contingency the vent 25 is made small enough not to give complete relief of the pumping impulses, so that when this vent is slightly open the compression in the column of air will be of sufficient force within the pumping chamber to cause discharge of the liquid fuel from the pumping chamber to the carburetor float chamber 3 above it. It will be noted that the valve 29 is arranged to open

inwardly so that compression impulses tend to close the valve when it is but a minute distance off of its seat, but suction impulses tend to open it. This will tend to trap a sufficient amount of pressure within the pumping chamber to overcome the head of the column of liquid between the pumping chamber and the float chamber. In this form it is more desirable to close off the inlet check valve 17 so that only the pressure impulses are operative during the time that the level within the pumping chamber 4 is high enough to cause opening of the vent.

The vent under this condition operates as sufficient relief for the suction impulses to prevent the drawing of more fuel through the check valve 17 but permits the pressure impulses to discharge fuel from the pumping chamber.

Where the pumping chamber is placed above the float chamber of the carburetor, fuel will discharge by gravity through the outlet check valve 15 and the vent 25 may then be great enough to relieve completely both kinds of pumping impulses.

In Fig. 5 I have illustrated a modification in which the vent 34 comprises a tube opening at its upper end into the top of the pumping chamber 4', is fastened in the lower wall of the pumping chamber and communicates with the atmosphere through the opening 27 in the cap member 26. The upper end of the tube 35 provides a valve seat with which the needle valve 36 cooperates to close off the vent from the interior of the chamber. The needle valve 36 is mounted on a bracket 37, secured to the top of the float 38. The inlet valve 17 is eccentrically disposed in the chamber 4'.

The operation of the form shown in Fig. 5 is substantially the same as described in connection with the previous figure.

It is to be noted that any rise or fall in the average pressure condition of the air chamber constituting the pipe 5 and cylinder 6 with respect to atmosphere, does not interfere with the operation of the system, inasmuch as the general atmospheric conditions will be established within said air chamber by the leakage past the piston 6, which operates as a breather. In fact, in my experiments heretofore, I find that this is a distinct advantage in that the piston need not be made to fit with great accuracy, and I have also operated the system with a minute breathing hole in the side walls of the air chamber.

I do not intend to be limited to the details of construction shown and described except as such details are specified in the appended claims.

I claim:

1. In combination, a pumping chamber having an inlet valve and an outlet valve for liquid to be pumped, a substantially closed

- air chamber inclosing a column of air and communicating with the top of said pumping chamber, one wall of said air chamber being movable to produce compressions and rarefactions in said column of air, a vent opening in the upper part of said pumping chamber, and a level controlled valve in said pumping chamber governing said vent.
2. In combination, a pumping chamber having an inlet valve and an outlet valve for liquid to be pumped, a substantially closed air chamber inclosing a body of air and communicating with the top of said pumping chamber, a piston forming a movable wall of said chamber, said piston having means governed by the engine to produce compressions and rarefactions in said column of air, a float in said pumping chamber, a vent in the upper part of said pumping chamber, and a valve for the vent controlled by said float.
3. In combination, a pumping chamber having inlet and outlet valves for pumping liquid fuel or the like, a substantially closed air chamber, inclosing a body of air communicating with the upper part of the pumping chamber, a carbureter float chamber communicating with the outlet valve of the pumping chamber, said air chamber comprising a movable piston for producing compressions and rarefactions in the body of air, and means for operating said piston from the motion of the engine, said pumping chamber being below the level of the carbureter float chamber.
4. In combination, a pumping chamber having inlet and outlet valves, a carbureter float chamber communicating with the outlet valve, said float chamber being above the level of the pumping chamber, an air chamber communicating with the top of the pumping chamber, said air chamber having as one wall thereof a piston movable in a cylinder, and a vent governed by the level
- of the liquid in the pumping chamber at the top of said pumping chamber.
5. In combination, a liquid pumping chamber having inlet and outlet valves, an air chamber communicating with the top of the pumping chamber, said air chamber having a movable wall for producing compressions and rarefactions of air in said air chamber, a vent in the top of said pumping chamber, a valve governing said vent, and level controlled means governing said vent controlling valve and the inlet valve of the pumping chamber.
6. In combination, a pumping chamber having inlet and outlet valves, a receiving chamber communicating with the outlet valve of the pumping chamber, said receiving chamber having means governing the discharge of liquid from the pumping chamber to the receiving chamber, an air chamber communicating with the top of the pumping chamber, said air chamber having a movable wall for producing compressions and rarefactions in the body of air in said air chamber, and means within the pumping chamber controlling the application of the pumping impulses to the liquid in said pumping chamber, said pumping chamber being below the level of said receiving chamber.
7. In combination, a liquid pumping chamber having inlet and outlet valves, an air chamber communicating with the pumping chamber, said air chamber having a movable wall for producing compression and rarefactions of air in said air chamber and a float in said chamber, said float having means for closing the inlet valve when the level in the pumping chamber rises above a predetermined level.

In witness whereof I hereunto subscribe my name this 14th day of February, A. D. 1918.

FRANCIS EDWIN EDWARDS.
